UNITED STATES PATENT AND TRADEMARK OFFICE
CERTIFICATE OF CORRECTION

PATENT NO. : D678,902 S
APPLICATION NO. : 29/386436
DATED : March 26, 2013
INVENTOR(S) : Matt Evans

Page 1 of 1

It is certified that error appears in the above-identified patent and that said Letters Patent is hereby corrected as shown below:

On the title page, item (57), claim section, please replace “an” with --a--.

On the title page, item (57), description section, line 2, please replace “our” with --my--.

Signed and Sealed this
Twenty-fourth Day of September, 2013

Teresa Stanek Rea
Deputy Director of the United States Patent and Trademark Office
